TABLE

Emil Senft, Cleveland, Ohio

Application November 3, 1938, Serial No. 238,669

3 Claims. (Cl. 311—85)

This invention relates to an improved table provided with folding legs and means for simultaneously extending and folding said legs.

More particularly, it is an aim of this invention to provide an improved card table provided with pivotally mounted legs and provided with means, of simple and durable construction, for simultaneously extending or folding said legs and for retaining the legs in an extended position.

Still a further aim of the invention is to provide a set of folding legs arranged in pairs at opposite ends of a table to fold against the underside thereof in overlapping relationship, and means for simultaneously extending or folding said legs including bars slidably mounted relatively to the table and adjacent the ends thereof with each of said bars connected at its ends to a pair of the legs.

Other objects and advantages of the invention will hereinafter become more fully apparent from the following description of the drawings, which illustrate a preferred embodiment thereof, and wherein:

Figure 1 is a bottom plan view of a table constructed in accordance with the invention,

Figure 2 is a side elevational view showing the table extended, as it would appear with one of the marginal edges of the table top removed,

Figure 3 is a longitudinal vertical central sectional view, on an enlarged scale, showing the parts in extended positions,

Figure 4 is an enlarged vertical sectional view taken along the line 4—4 of Figure 2,

Figure 5 is an enlarged vertical sectional view taken along the line 5—5 of Figure 4,

Figure 6 is an enlarged vertical sectional view taken along the line 6—6 of Figure 3, and

Figure 7 is a bottom plan view on a reduced scale, of the operating mechanism only, shown in an extended position.

Referring more particularly to the drawings, wherein like reference characters designate like or corresponding parts throughout the different views, 10 designates generally a card table shown to illustrate a preferred embodiment of the invention. The table 10 includes the table top 11, provided with the marginal depending frame or flange 12 and having the longitudinally disposed reinforcing members 13, extending along the underside thereof.

A pair of connecting bars 14 are pivotally mounted at their ends on the flange 12, adjacent to the opposite ends of the table 10 and on the underside thereof. A pair of legs 15 is secured to each of the bars 14 by means of the brackets

16. A leg 15 is secured to an end of each bar 14 at opposite ends of said bars to lie along the side portions of the flange 12 when in a folded position, while a leg 15 is secured in spaced relationship to the other end of each bar to fold into a position at the inner side of the outer legs so that the legs of each pair, when folded, are disposed in overlapping side by side relationship, as best seen in Figure 1.

Brace members 13 are provided with the slots 17, adjacent their ends, in which are slidably mounted the transversely disposed bars 18 which are held in position therein by means of the strips 19 secured to the underside of the table top 11 and adapted to slidably engage the notches 20, as seen in dotted lines in Figure 5. Bars 18 are slightly offset relatively to each other so that one bar 18 projects beneath one of the inner legs 15, adjacent one side of the table 10 while the other bar 18 projects beneath the other inner leg 15 adjacent the opposite side of the table.

Brace members 21 are pivotally connected by the fastenings 22 to the ends of the bars 18 and to the legs 15, adjacent their secured ends with each bar being connected at its ends to a pair of the legs 15 which are connected to a bar 14. The braces 21 which connect with the outer legs 15 are disposed between the adjacent legs, when folded, as seen in Figure 1.

A brace member 23 is secured to the underside of the top 11 and disposed transversely thereof, and intermediate of its ends. A lever 24 is pivotally connected intermediate of its ends, at 25, to the member 23. The lever 24 is provided at its ends with depending studs 26 which project into slots 27, in the opposite ends of the bars 18. The slots 27 have their inner ends disposed in overlapping relationship, as best seen in Figure 1, so that when the lever 24 is in an extended position, as seen in Figure 7, the studs 26 will engage the inner ends of the slots 27 and the lever 24 will be substantially at right angles to the bars 18, to retain the bars 18 and the legs 15 in extended positions.

Brace members 13 at their ends are recessed, as indicated at 13', to accommodate the connecting bars 14 so that all of the parts of the table 10 may fold into the space bound by the flange 12.

From the foregoing it will be obvious, that lever 24 may be actuated for simultaneously moving the legs 15 from a folded position, as seen in Figure 1, to an extended position, as seen in Figures 2 and 7, by swinging the lever 24 from its diagonal position, as seen in Figure 1, to a

position substantially at right angles to the bars 18 to cause said bars to be projected. The lever 26 being substantially at right angles to bars 18, when the bars are extended, will prevent the legs from being accidentally folded or collapsed. The braces 21, which form links for connecting the ends of the bars 18 and the legs 15, while the legs are being opened and closed, form braces for rigidly holding the legs when in their open positions. Connecting bars 14 cooperate with the braces 21 for rigidly supporting the legs relatively to the table top 11 and this is in fact the only function which bars 14 have as the legs could be hinged to the underside of the table top 11 and would still swing simultaneously to an open or closed position when the lever 24 is actuated. By swinging lever 24 in the opposite or a counterclockwise direction, the studs 26 will move along the slots 27 to retract bars 18 to draw the legs 15 inwardly to their folded positions.

Various other modifications and changes in the construction and arrangement of the parts forming the invention are contemplated and may obviously be resorted to and the right is therefore expressly reserved to make such variations and changes as do not depart from the spirit and scope of the invention as hereinafter defined by the appended claims.

I claim as my invention:

1. A table comprising a table top, legs pivotally connected thereto adjacent the four corners thereof, bars slidably mounted relatively to said table top, links connecting the ends of said bars

and said legs, a lever pivotally connected to said table top, intermediate of its ends, and to said bars for projecting the bars when the lever is swung to a position at right angles thereto for swinging the legs to their extended positions, said bars being provided with slots, and studs projecting from the ends of said lever for engaging said slots for projecting and retracting said bars when the lever is swung relatively thereto.

5 2. A table having pairs of legs pivotally connected thereto and disposed adjacent the corners thereof, a lever pivotally connected intermediate of its ends to the table, bars slidably mounted on said table, links pivotally connected to said bars and to the legs, adjacent their pivoted ends, said bars being provided with longitudinal slots extending from adjacent their centers in opposite directions, and lugs on the ends of said lever for slidably engaging the slots to project and retract them relatively to each other for opening and closing the legs.

15 3. A table having pairs of legs pivotally connected thereto and disposed adjacent the corners thereof, a lever pivotally connected intermediate of its ends to the table, bars slidably mounted on said table, links pivotally connected to said bars and to the legs, adjacent their pivoted ends, and said lever being slidably connected at its ends to said bars, for projecting and retracting the bars, when the lever is swung relatively to the table, for opening and closing the legs as a unit.
